AUTOMATIC PRESSER FOOT MECHANISM

Filed Oct. 3, 1923

2 Sheets-Sheet 2

UNITED STATES PATENT OFFICE.

LEO J. DU MAIS AND FLOYD E. MINER, OF CHICAGO, ILLINOIS, ASSIGNEES TO CHICAGO SHOE MACHINERY COMPANY, OF CHICAGO, ILLINOIS, A CORPORATION OF ILLINOIS.

AUTOMATIC PRESSER-FOOT MECHANISM.

Application filed October 3, 1923. Serial No. 666,236.

To all whom it may concern:

Be it known that we, LEO J. DU MAIS and FLOYD E. MINER, citizens of the United States, and residents of Chicago, in the county of Cook and State of Illinois, have invented certain new and useful Improvements in Automatic Presser-Foot Mechanism, of which the following is a specification.

10 This invention relates, generally, to improvements in sewing machines, and more particularly to leather stitching or sewing machines of the type which employ an oscillatory curved awl for piercing and feeding the work and an oscillatory curved needle having a notch near its free end for engaging the thread, said awl and needle operating from opposite sides of the work, but particularly to an automatic presser-foot mechanism therefor.

15 The principal object of the invention, is the provision of a novel and improved mechanism for actuating and locking the presser-foot intermittently, by means of which mechanism the presser-foot is operated for clamping and automatically and positively locking the work on the work-support of the machine during the greater portion of a cycle, or during the stitch forming operation, and for releasing it from the work during the lesser portion of the cycle, or during the work-feeding movement of the awl.

20 Other objects of the invention, are, to provide yielding means to hold the presser-foot in engagement with the work in such a way as to permit it to accommodate itself to different thickness of the work and manually operable means for releasing said locking means and raising the presser-foot at any time during the cycle, whereby the work may be inserted, adjusted or withdrawn.

25 Numerous other objects and advantages of the invention will become apparent from the following description and explanation.

The invention consists in the parts and in the arrangement and combinations of parts hereinafter described and claimed.

30 In the accompanying drawings, which serve to illustrate an embodiment of the invention, and in which corresponding numerals of reference refer to like parts throughout the different views thereof,—

Fig. 1 is a view in side elevation of a

portion of the supporting frame of a leather stitching machine showing the mechanism mounted thereon and only the parts of the machine which are directly associated with the present invention.

Fig. 2 is a front face view of the parts 60 in the same relation to one another as shown in Fig. 1.

Fig. 3 is a view somewhat similar to Fig. 1 showing parts of the supporting frame of the machine, a part of the cam which operates the mechanism illustrating the locking mechanism for the presser-foot, a portion of which has been broken away to disclose said locking mechanism. In this view the parts are shown in the positions they 70 will assume just prior to the locking engagement of the presser-foot with the work.

Fig. 4 is a detached perspective view of the upper portion of the locking lever of the device, and

Fig. 5 is a detached perspective view of the trigger or releasing member for the jaw of the locking lever.

Referring to the drawings, the reference numeral 6 designates a portion of one of the uprights on which the main or drive shaft 7 of the machine is transversely and horizontally mounted rearwardly of the uprights or standards 8 at the front portion of the machine, which standards are spaced 80 apart laterally and carry at their upper portions a horizontally disposed shaft 9 upon which shaft the needle and awl of the machine is mounted for oscillatory movement on opposite sides of the work support, the 90 said shaft being mounted for longitudinally slidable movement or reciprocation so as to afford lateral movement to the awl, all of which is well known to those skilled in the art, and for this reason it has been 95 deemed unnecessary to illustrate in detail.

In the drawings, only one of the uprights 8 is shown, but it will be understood that a work support 10 of the usual construction is mounted transversely on the upper portion of the upright 8 shown and similarly on the other upright which is not shown, and is extended forwardly therefrom. The presser-foot comprises a bar or member 11 having at its upper end a lateral and substantially horizontal extension 12 which lies over the work support 10 and has a slot 13 therein through which the needle and awl

work. The work support 10 is provided with an elongated opening 14 for the reception of the awl 16 of the machine, which opening is located longitudinally in the work support so as to permit sidewise movement of the awl in its feeding operation. The presser-foot designated as a whole by the numeral 11 is pivotally mounted on a shaft 15 on the upper portion of the standard 8 rearwardly of the awl and needle carrying shaft 9, as is clearly shown in Fig. 1 of the drawing.

The presser-foot 11 is provided at its lower end with a handle 17 and at the juncture of said handle with the shank of the presser-foot with a laterally disposed pin 18 to which is secured one end of a helical spring 19, the other end of which is secured to a pin 20 on the standard 8 at a suitable point thereon.

Mounted on the drive shaft 7 to turn therewith, is a disk 21 which is provided in one of its faces with a cam groove 22 for co-operation with a roller 23 journaled on an arm 24 extended from a link 25 which is pivotally connected at its upper end to an arm 26 of the standard 8 and is similarly connected at its lower end to a bar 27 which is located near the lower portion of the cam face of the disk 21 and extends forwardly and substantially horizontally near the side of the shank 11^a of the presser-foot adjacent the standard 8 and is movably supported near its free end by a roller 28 journaled on the lower portion of said shank. This bar is provided on its upper surface from its front end rearwardly to a suitable distance with transverse serrations or teeth 29 to mesh with or engage teeth 30 on a jaw or block 31 which is rigidly secured to that side of the upper portion of the locking lever 32 adjacent the inner surface of the shank 11^a of the presser-foot, on which surface of said shank the lever 32 is fulcrumed by means of a suitable pivot 33 extended through a suitable opening in the upper portion of the lever 32 and through the opening 34 in the block 31. The upper portion of the lever 32 is extended forwardly and somewhat below the pivot 33 and has on its said lower portion a pin 35 which is laterally extended towards the standard 8 and is for co-action with the releasing trigger or member for the locking mechanism, as will be presently explained.

The above mentioned trigger or member comprises an elbow-shaped piece 36 having its front end downwardly and rearwardly beveled as at 37, see Figs. 3 and 5, for slideable co-action with a pin 38 which is eccentrically mounted on the surface of the standard 8 adjacent the lever 32 at a point below and forwardly of the pivot or fulcrum of said lever.

65 By mounting the pin 38 eccentrically on

the standard 8, it is manifest that by turning it in the proper direction, the bearing surface thereof for the beveled end 37 of the trigger 36 can be adjusted as desired. The trigger 36 is provided at its end opposite the beveled end 37 with a laterally extended apertured boss 39 and said boss is provided at its lower portion with a lateral extension or foot 40 for co-operation with the bar 27, on the surface of which adjacent the lever 32, said trigger is pivotally secured by means of a bolt 41 extended through the aperture of said boss and a suitable opening in the bar 27 at a point therein rearwardly of the rear edge of the shank 11^a of the presser-foot.

On its side adjacent the shank 11^a of the presser-foot, the bar 27 is provided with a stop member 42 for co-action with the rear edge or surface of said shank, and in the present instance is shown in the form of an elongated plate mounted on the bolt 41 and held in place by means of a nut 43 in threaded engagement with the said bolt, but it will be understood that any other stopping device may be employed.

As is clearly shown in Figs. 1 and 3, the locking lever 32 is extended downwardly to about the same extent as is the lower end of the presser-foot 11 and said lever is equipped with a handle portion 44 at its lower extremity. A spiral spring 45 is interposed between the handle portions 17 of the presser-foot and the portion 44 of the locking lever for the purpose of exerting its tension against the last named handle portion to thereby cause the jaw 31 and the upper portion of the locking lever to be actuated downwardly and forwardly of its fulcrum, which operation will automatically hold the toothed jaw 31 and the pin 35 on the lower front portion of the lever 32 in position to engage the teeth 29 of the bar 27 and the upper surface of the front part of the trigger 36, except when said trigger is manipulated, by causing the parts of the mechanism to assume about the positions shown by dotted lines in Fig. 1 of the drawings. When in such positions, it is manifest that the extension 12 of the presser-foot will be raised to a considerable distance above the work-support 10, thus permitting the insertion, adjustment or withdrawal of the work. When the parts are in the positions shown by continuous lines in Fig. 1, it will be observed that the beveled end 37 of the trigger will be retracted rearwardly from the pin 38 with which it co-acts as well as with the pin 35, to throw the jaw teeth out of engagement with the teeth of the said bar, and to cause the trigger to maintain the above mentioned position until the bar is reciprocated forwardly. The rear end of the trigger or rather the lower portion of the lateral boss 39 thereon,

is provided with the lateral extension 40 to engage the lower edge of the bar as shown in Fig. 1 of the drawings.

Having thus fully described our invention, what we claim as new and desire to secure by Letters Patent is:

1. In a sewing machine, the combination with a work-support, of a pivoted presser-foot co-operating therewith, a spring to actuate said foot in one direction, a locking lever fulcrumed on said foot and having a portion extended forwardly and below its fulcrum provided with a lateral jaw, cam controlled means including a reciprocatory bar co-operating directly with said jaw for locking the foot against pivotal movements, and means carried by said bar for engagement with a part of the front portion of said lever for releasing said locking means. 55
2. In a sewing machine, the combination with a work-support, of a spring-actuated pivoted presser-foot co-operating therewith, a locking lever fulcrumed on said foot and having a portion extended forwardly and below its fulcrum provided with a lateral jaw having teeth on its lower extremity, cam controlled means including a reciprocatory bar having teeth for co-operation with the teeth of said jaw for locking the foot against pivotal movements, and means carried by said bar for engagement with a part of the front portion of said lever for releasing said locking means. 60
3. In a sewing machine, the combination with a work-support, of a pivoted presser-foot co-operating therewith, a locking lever fulcrumed on said foot and having a portion extended forwardly and below its fulcrum provided with a lateral jaw having teeth on its lower extremity, said lever having at its lower portion a handle, a spring to actuate said foot in one direction, a vertically disposed locking lever fulcrumed on said foot and having a portion extended forwardly and below its fulcrum provided with a lateral jaw having teeth on its lower extremity, said lever having at its lower portion a handle spaced from the handle of the presser-foot, a spring interposed between said handles, cam controlled means including a reciprocatory bar having teeth for co-operation with the teeth of said jaw for locking the foot against pivotal movements, an upwardly and forwardly extended trigger pivotally mounted at its rear end on said bar rearwardly of the fulcrum of the locking lever having its front end downwardly and rearwardly beveled and adapted for engagement with a part on the front portion of said lever, and a fixed pin located in the path of the beveled end of said trigger whereby said locking means will be released. 65
4. In a sewing machine, the combination with a work-support, of a pivoted presser-foot co-operating therewith, a spring to actuate said foot in one direction, a locking lever fulcrumed on said foot and having a portion extended forwardly and below its fulcrum provided with a lateral jaw having teeth on its lower extremity, a cam, a link pivoted at one end on a fixed pivot, a roller carried by said link and co-operating with said cam, a bar pivotally secured at its rear end to the lower portion of said link and having teeth on its upper front portion for engagement with the teeth of said jaw, said bar being supported for reciprocatory movement, a trigger pivotally mounted at its rear end on said bar and having its opposite end downwardly and rearwardly beveled, a projection fixed in the path of the beveled end of said trigger, the upper portion of the front part of said trigger being downwardly and forwardly inclined and adapted for engagement with a part on the front portion of said locking lever whereby in the forward movement of said bar the said locking means will be released. 70
5. In a sewing machine, the combination with a work-support, of a vertically disposed presser-foot co-operating therewith and having at its lower portion a handle, a spring to actuate said foot in one direction, a vertically disposed locking lever fulcrumed on said foot and having a portion extended forwardly and below its fulcrum provided with a lateral jaw having teeth on its lower extremity, said lever having at its lower portion a handle spaced from the handle of the presser-foot, a spring interposed between said handles, cam controlled means including a reciprocatory bar having teeth for co-operation with the teeth of said jaw for locking the foot against pivotal movements, an upwardly and forwardly extended trigger pivotally mounted at its rear end on said bar rearwardly of the fulcrum of the locking lever having its front end downwardly and rearwardly beveled and adapted for engagement with a part on the front portion of said lever, and a fixed pin located in the path of the beveled end of said trigger whereby said locking means will be released by the forward movement of said bar. 75
6. In a sewing machine, the combination with a work-support, of a pivoted presser-foot co-operating therewith, a spring to actuate said foot in one direction, a locking lever fulcrumed on said foot and having a portion extended forwardly and below its fulcrum provided with a lateral jaw having teeth on its lower extremity, a cam, a link pivoted at one end on a fixed pivot, a roller carried by said link and co-operating with said cam, a bar pivotally secured at its rear end to the lower portion of said link and having teeth on its upper front portion for engagement with the teeth of said jaw, said bar being supported for reciprocatory movement, a trigger pivotally mounted at its rear end on said bar and having its opposite end downwardly and rearwardly beveled, a projection fixed in the path of the beveled end of said trigger, the upper portion of the front part of said trigger being downwardly and forwardly inclined and adapted for engagement with a part on the front portion of said locking lever whereby in the forward movement of said bar the said locking means will be released. 80
7. In a sewing machine, the combination with a work-support, of a pivoted presser-foot co-operating therewith, a spring to actuate said foot in one direction, a locking lever fulcrumed on said foot and having a portion extended forwardly and below its fulcrum provided with a lateral jaw having teeth on its lower extremity, said lever having at its lower portion a handle spaced from the handle of the presser-foot, a spring interposed between said handles, cam controlled means including a reciprocatory bar having teeth for co-operation with the teeth of said jaw for locking the foot against pivotal movements, an upwardly and forwardly extended trigger pivotally mounted at its rear end on said bar rearwardly of the fulcrum of the locking lever having its front end downwardly and rearwardly beveled and adapted for engagement with a part on the front portion of said lever, and a fixed pin located in the path of the beveled end of said trigger whereby said locking means will be released by the forward movement of said bar. 85
8. In a sewing machine, the combination with a work-support, of a pivoted presser-foot co-operating therewith, a spring to actuate said foot in one direction, a locking lever fulcrumed on said foot and having a portion extended forwardly and below its fulcrum provided with a lateral jaw having teeth on its lower extremity, a cam, a link pivoted at one end on a fixed pivot, a roller carried by said link and co-operating with said cam, a bar pivotally secured at its rear end to the lower portion of said link and having teeth on its upper front portion for engagement with the teeth of said jaw, said bar being supported for reciprocatory movement, a trigger pivotally mounted at its rear end on said bar and having its opposite end downwardly and rearwardly beveled, a projection fixed in the path of the beveled end of said trigger, the upper portion of the front part of said trigger being downwardly and forwardly inclined and adapted for engagement with a part on the front portion of said locking lever whereby in the forward movement of said bar the said locking means will be released. 90
9. In a sewing machine, the combination with a work-support, of a pivoted presser-foot co-operating therewith, a spring to actuate said foot in one direction, a locking lever fulcrumed on said foot and having a portion extended forwardly and below its fulcrum provided with a lateral jaw having teeth on its lower extremity, said lever having at its lower portion a handle spaced from the handle of the presser-foot, a spring interposed between said handles, cam controlled means including a reciprocatory bar having teeth for co-operation with the teeth of said jaw for locking the foot against pivotal movements, an upwardly and forwardly extended trigger pivotally mounted at its rear end on said bar rearwardly of the fulcrum of the locking lever having its front end downwardly and rearwardly beveled and adapted for engagement with a part on the front portion of said lever, and a fixed pin located in the path of the beveled end of said trigger whereby said locking means will be released by the forward movement of said bar. 95
10. In a sewing machine, the combination with a work-support, of a pivoted presser-foot co-operating therewith, a spring to actuate said foot in one direction, a locking lever fulcrumed on said foot and having a portion extended forwardly and below its fulcrum provided with a lateral jaw having teeth on its lower extremity, a cam, a link pivoted at one end on a fixed pivot, a roller carried by said link and co-operating with said cam, a bar pivotally secured at its rear end to the lower portion of said link and having teeth on its upper front portion for engagement with the teeth of said jaw, said bar being supported for reciprocatory movement, a trigger pivotally mounted at its rear end on said bar and having its opposite end downwardly and rearwardly beveled, a projection fixed in the path of the beveled end of said trigger, the upper portion of the front part of said trigger being downwardly and forwardly inclined and adapted for engagement with a part on the front portion of said locking lever whereby in the forward movement of said bar the said locking means will be released. 100
